Attorney

UNITED STATES PATENT OFFICE.

ALBERT G. HOFAMMANN, OF ALLENTOWN, PENNSYLVANIA.

SHUTTLE GUARD.

Application filed December 18, 1925. Serial No. 76,192.

My invention relates to a guard intended for attachment to a loom, such as are used for the weaving of silk cloth, for example. As is well known, it occasionally happens that for various reasons the shuttle used in weaving cloth is deflected from its course. In view of the speed at which the shuttle normally operates it is evident that such deflection constitutes a source of grave danger to anyone who may be at that time near the loom. It is the object of this invention to provide a guard of extremely simple and practical design that will not only effectually prevent the shuttle from being so far deflected from its course as to render anyone liable to injury, but that will at the same time return the shuttle to its course should deflection occur.

A further object of the invention is to provide a guard that does not interfere with the work of the weaver upon the reed.

A still further object is to provide a guard that will automatically assume a protective position should the weaver start the loom without adjusting the guard to said position.

Further objects will appear as the description proceeds.

In the drawings,

Figure 1 is a front elevation showing my improved device attached to the hand rail of the loom.

Figure 2 is a cross section view on an enlarged scale taken on the plane of the line 2—2 in Fig. 1, looking in the direction of the arrows.

Figure 3 is a cross section on the line 3—3 of Fig. 2.

Figure 4 is a cross sectional view on the plane indicated by the line 4—4 on Fig. 1.

Similar reference characters indicate the same parts in the several figures.

The numeral 1 indicates the hand rail of the loom to which my improved device is attached. As is well understood by those skilled in the art to which this invention pertains, the shuttle reciprocates rapidly beneath the hand rail between the shuttle boxes arranged at the ends of said rail. The usual reed and lay beam of the loom are in back of and below the path of movement of the shuttle. These parts have not been shown on the drawing as they are well

known in the art and constitute no part of my invention.

My guard consists of brackets 2 attached to the hand rail by screws 4 passing through the attaching flanges 3 of said brackets. Each bracket is provided with an outwardly projecting portion 5 provided with curved slots 6. The slots, as will be apparent from the drawings, are so formed that at their inner ends they extend horizontally. From their horizontal portion they extend smoothly downwardly. Arranged to move in the slots of said brackets are round rods 7 and 8.

The rod 8 is held from endwise movement and guided in its downward movement by a collar 9 fixed thereto, fitting in a groove 10 cut in one of the brackets as clearly shown in Figs. 2 and 3.

The rod 7 is held from endwise movement and guided in its movement through the slots by collars 11 fixed to said rod on opposite sides of one of the brackets.

Each bracket is provided with a nose portion 12 projecting therefrom. The surfaces of said portions are inclined so that when the deflected shuttle is guided by the rods 7 and 8 to the brackets the engagement of the nose of the shuttle with said inclined surfaces will return the shuttle to its prescribed course.

In operation, the rods are in the position shown in Fig. 1. If it is necessary for the weaver to get to the reed as for the purpose of piecing up, for example, he moves the rods 7 and 8 to the position shown in dotted lines in Fig. 2. As the slots at this position extend horizontally, the rods will remain in their upper position. However, in view of the absence of any holding means, it will be readily appreciated that should the weaver negligently fail to move the rods to their lower or protective position, the vibration of the loom will immediately cause the rods to roll down the smoothly curved slots into their effective position.

It will thus be seen that an effective shuttle guard is provided consisting of few and simple parts, that is automatic in operation, and that in view of the absence of holding means the guard will immediately upon starting the loom, assume its operative position.

The invention has been described in detail above. It should be understood that the invention is not limited to said details, but includes all variations that fall within the scope of the following claims.

I claim as my invention:

1. A shuttle guard for a loom including a bracket, provided with a slot, a second slotted bracket, a rod extending between said brackets, a collar fixedly secured to said rod to hold said rod against endwise movement, an elongated groove in said first mentioned bracket extending parallel and coextensive with the slot in that bracket, said groove receiving said collar, whereby movement of the rod in the direction of the slot is permitted.

2. A shuttle guard for a loom comprising a pair of spaced brackets designed for attachment to said loom, each bracket being provided with a plurality of separate slots, each slot including a smooth horizontal or shelf portion and a forwardly and downwardly curved portion, the downwardly curved portion of one slot terminating substantially above the end of the downwardly curved portion of the other slot, a plurality of independently operable rods having ends of substantially circular cross section extend-

ing between said brackets with said ends arranged in said slots, said rods being free to move relative to each other and to said brackets in said slots so that each rod will automatically seek its operative position in the downwardly curved portion of the slot in which it is mounted when the loom is started.

3. A shuttle guard for a loom comprising a plurality of brackets designed for attachment in spaced relation to said loom, each bracket being provided with a pair of slots each comprising a horizontally extending or shelf portion and a curved portion extending downwardly from said first named portion, the curved portion of one of said slots in each bracket being substantially longer than the curved portion in the other slot of said bracket, a rod provided with cylindrical ends freely movable in the longer slots of adjacent brackets and a second rod having substantially cylindrical ends freely movable in the shorter slots of adjacent brackets, the arrangement being such that each of said rods is free to roll from the shelf portion to the end of the curved portion of the slot in which it is mounted when the loom is started.

ALBERT G. HOFAMMANN.
